AIR-COOLED INTERNAL-COMBUSTION ENGINE

Joseph M. Colby, Grosse Pointe, Mich.

Application October 2, 1946, Serial No. 700,632

10 Claims. (Cl. 60—13)

(Granted under the act of March 3, 1883, as amended April 30, 1928; 370 O. G. 757)

1

The invention described herein may be manufactured and used by or for the Government for governmental purposes, without the payment to me of any royalty thereon.

This invention relates to internal combustion engines, and particularly to multi-cylinder internal combustion engines whose cylinders and valves are air-cooled by means of fans or blowers.

In order that a multi-cylinder internal combustion engine be cooled by air, it is necessary that a large amount of cooling air be continuously distributed equally over all of the exterior surface of each of the cylinders. In addition in order that such cooling be done efficiently and with a minimum expenditure of power, it is necessary in producing this required large amount of cooling air that the number of fans or blowers be reduced to a minimum, and that the currents of cooling air so produced travel in the line of least resistance, i. e., with a minimum of deflection and through the shortest possible effective distance while still retaining the necessary continuous, equal and thorough distribution of the large amount of cooling air required.

Heretofore the air-cooling of multi-cylinder internal combustion engines involved, for example, the providing of one or more blowers at the end of the engine or below the engine, together with deflecting conduits or baffles for deflecting the cooling air to each of the cylinders, or the providing of individual air passages encasing each cylinder, together with means for conducting or distributing the cooling air from the blower or blowers to each of the individual air passages, such types of construction necessarily involving a relatively long distance of travel and also considerable deflection of the cooling air which necessitates the use of increased horsepower of the blowers to overcome the resistance to the flow of air, as well as occupying space for the cooling apparatus which could well be utilized for other purposes.

The object of the present invention broadly is to provide a compact multi-cylinder internal combustion engine which is air-cooled, simply and efficiently with a minimum power requirement consistent with the amount of cooling air required.

More specifically the object of the present invention is to provide a compact, air-cooled, multi-cylinder internal combustion engine in which the number of blowers or fans required for air-cooling, the length of travel of the cooling air, and deflection of the cooling air are reduced to a minimum.

In accordance with this invention, the air-cooling of a multi-cylinder internal combustion engine is accomplished simply and efficiently by means of one or more blowers comprising rotary axial flow fans adjacent to the cylinders and positioned to rotate in a common plane parallel to the axis of the crankshaft with the axis of each blower being perpendicular to that of the crankshaft. Each blower is mounted on a blower shaft which is perpendicular and geared to a common auxiliary shaft which may be the camshaft, the common auxiliary shaft being parallel to the crankshaft and preferably geared, but may be belted, thereto. Rotation of the crankshaft supplies the power for rotation of the auxiliary shaft and each individual perpendicular blower shaft geared thereto and carrying a blower.

By way of example, the following description and drawings illustrate some embodiments of the invention:

Figure 1 is a plan view of a V-type, 12-cylinder, air-cooled engine, with two rotary axial flow fans positioned at the top of the engine between the two rows of cylinders, and illustrating the present invention.

Figure 2 is a side elevation of the same engine, partly broken away to show the drive mechanism of the fans.

Figure 3 is an end elevation of the same engine, partly broken away.

Figure 4 is a diagrammatic side elevation view of fans in the same engine showing the addition of contra vanes adjacent one type of fan blades.

Figure 5 is a diagrammatic view of one of the fans showing one type of fan construction.

Figure 6 is a plan view of a horizontally opposed or pancake type engine installation embodying this invention and utilizing one rotary axial flow fan.

Figure 7 is a plan view partly broken away of the engine of Figure 6, but showing two rotary axial flow fans in accordance with this invention.

Figure 8 is an end elevation partly broken away of the construction shown in Figure 7.

Figure 9 is an end elevation of an X-type engine installation embodying this invention.

In the drawings, wherein like numerals refer to similar parts throughout, Figures 1, 2 and 3 show an engine wherein two banks of cylinders 12 and 12', having the usual pistons (not shown), are connected in V-formation in the usual manner with crankcase 11 covering a crankshaft 15 to which as usual the pistons are operatively connected (not shown). A shroud 22 fits over two

rotary axial flow fans 14 and 14', which are positioned at the top, between the two banks of cylinders 12 and 12' and adjacent the sides thereof, to rotate in a common plane parallel to the axis of crankshaft 15 with their axes perpendicular thereto. Fans 14 and 14' are mounted on individual blower shafts 16 and 16', which blower shafts are perpendicular to a common auxiliary shaft 17 and geared thereto as by bevel gears 19 and 20. Common auxiliary shaft 17 is parallel to crankshaft 15 and geared thereto by gears 21 and 26.

Detailed examples of blower construction in accordance with this invention are shown in Figures 4 and 5.

In Figure 4 a construction employing two blowers is shown. Each blower comprises a rotary axial flow fan 14 or 14' having one set of blades 24. These are suction fans and preferably draw air from across the cooling fins of the cylinders and upward between the shroud openings, as shown by the arrows in Figure 3. If desired, respective sets of stationary contra vanes shown at 25 in Figure 4 directly below blades 24 may be employed to assure straight line flow when the air is drawn across the cylinders and upward through the fan, the preferred method of operation, since the natural force of convection of the heated air will thus assist the movement of the air upward. If desired, however, the function of the fans 14 and 14' may be reversed, moving the cooling air downward through the blower and then across the cylinders in opposite direction to the arrows of Figure 3, in which case stationary contra vanes 25 will be positioned above blades 24. In Figure 5, and as also shown in Figures 1, 2 and 3, the axial flow fans may have two sets of blades consisting of an inner set of blades 24 for air, and an outer set of blades 23 as tips on blades 24, blades 23 being driven turbine fashion by exhaust jets 25a from the engine as shown in Figure 5, thus utilizing the engine exhaust to supplement the power for driving the fans and reducing the amount of driving power taken directly from the crankshaft, increasing the efficiency of operation.

In Figure 6 showing a plan view of horizontally opposed or pancake type of engine embodying the invention, only one blower or rotary axial flow fan is used, and its construction, as well as the driving mechanism, are similar to those above described.

In Figure 7 showing the same type of engine as in Figure 6, two auxiliary shafts 17 and 17' are shown, one adjacent each row of cylinders, for rotation of respective blower shafts 16 and 16', the latter being perpendicular to the axis of the crankshaft. On each blower shaft is mounted a fan (not shown) adjacent the side of one row of cylinders and with its axis perpendicular to the axis of the crankshaft.

In Figure 8 the arrangement of the fans and blower shafts of the construction of Figure 7 is more clearly shown.

In Figure 9 showing an end elevation of an X-type of engine embodying the invention, construction details are the same as above described with other types of engines, except that an auxiliary shaft 17 or 17' is required for each two rows of cylinders between which one or more rotary axial flow fans 14 or 14' are positioned for rotation in a common plane parallel to the axis of the crankshaft.

In operation, the course of air flow, shown by the arrows of Figure 3, is inwardly across the

fins of the cylinders to a central space as between the two rows of cylinders of the V-type engine, thence upwardly through the fans between the shroud openings and out, the flow upward being aided by the natural convection of the thus heated air. If desired, the direction of flow of air may be in a reverse direction to that shown, as by arranging for rotation of the blowers in an opposite direction, or by utilization of fan blades with opposite pitch. It will thus be seen that the large amount of cooling air required travels a minimum distance with a minimum deflection and at a consequent minimum expenditure of power, combined with the advantages of a relatively compact construction and with a minimum number of fans necessary.

Because of compactness and low resistance to cooling air flow, this construction is particularly advantageous in connection with a vehicle requiring a submerged installation, for example, a tank.

It will be appreciated that one or more blowers or rotary axial flow fans may be used as necessitated by the various types of engines for proper cooling consistent with minimum power expenditure and compactness.

Although I have shown and described certain embodiments of the invention, it will be understood that I do not wish to be limited to the exact construction shown and described, but that various changes and modifications may be made without departing from the spirit and scope of my invention as defined in the appended claims.

What I claim is:

35. 1. An improved air-cooled engine of the character described comprising, in combination, an internal combustion engine having a crankcase with a crankshaft therein and a plurality of rows of cylinders each equipped with air-cooling fins, at least one rotatably mounted auxiliary shaft with the axis thereof adjacent and parallel to the axis of said crankshaft, means operably connecting said auxiliary shaft to said crankshaft for drive rotation by the latter, at least one rotatably mounted blower shaft operably geared at one end thereof to said auxiliary shaft and extending therefrom upwardly and outwardly between two rows of said rows of cylinders, the axis of said blower shaft being perpendicular to the axes of said crankshaft and said auxiliary shaft, a bladed rotary axial flow suction fan mounted on the other end of said blower shaft for rotation with the latter and in a plane parallel to the axis of said crankshaft, the axis of said suction fan being perpendicular to the axis of said crankshaft, blades of said suction fan consisting of an inner and an outer set of blades, said inner set of blades being for air and extending in close proximity to said air-cooling fins of at least some of said cylinders, said outer set of blades being formed as tips on said inner set of blades, engine exhaust jets connected to said engine and positioned adjacent said outer set of blades for driving said fan with the aid of exhaust gases from said engine, a set of stationary contra vanes positioned adjacent and extending across said inner set of fan blades to assure straight line air flow, and a mounted fan shroud member having upper and lower open ends thereof and surrounding said suction fan adjacent outer ends of said outer set of blades thereof for directing flow of air from said air-cooling fins to said suction fan, said shroud member terminating at said lower open end thereof between said suction fan and said air-cooling fins, said suction fan by

operation of said engine being rotatable in a direction effecting the drawing of air from across the air-cooling fins of said cylinders and thence upwardly and outwardly through said upper open end of said fan shroud member.

2. An improved air-cooled engine of the character described comprising, in combination, an internal combustion engine having a crankcase with a crankshaft therein and a plurality of rows of cylinders each equipped with air-cooling fins, at least one rotatably mounted auxiliary shaft with the axis thereof adjacent and parallel to the axis of said crankshaft, means operably connecting said auxiliary shaft to said crankshaft for drive rotation by the latter, at least one rotatably mounted blower shaft operably geared at one end thereof to said auxiliary shaft and extending therefrom upwardly and outwardly between two rows of said rows of cylinders, the axis of said blower shaft being perpendicular to the axes of said crankshaft and said auxiliary shaft, a bladed rotary axial flow suction fan mounted on the other end of said blower shaft for rotation with the latter and in a plane parallel to the axis of said crankshaft, the axis of said suction fan being perpendicular to the axis of said crankshaft, blades of said suction fan extending in close proximity to said air-cooling fins of at least some of said cylinders, and a mounted fan shroud member having upper and lower open ends thereof and surrounding said suction fan adjacent the outer ends of said blades thereof for directing flow of air from said air-cooling fins to said suction fan, said shroud member terminating at said lower open end thereof between said suction fan and said air-cooling fins, said suction fan by operation of said engine being rotatable in a direction effecting the drawing of air from across the air-cooling fins of said cylinders and thence upwardly and outwardly through said upper open end of said fan shroud member.

3. An improved air-cooled engine of the character described comprising, in combination, an internal combustion engine having a crankcase with a crankshaft therein and two rows of cylinders each equipped with air-cooling fins, a rotatably mounted auxiliary shaft with the axis thereof adjacent and parallel to the axis of said crankshaft, means operably connecting said auxiliary shaft to said crankshaft for drive rotation by the latter, a plurality of rotatably mounted blower shafts each operably geared at one end thereof to said auxiliary shaft and extending therefrom upwardly and outwardly between said two rows of cylinders, the axis of each of said blower shafts being perpendicular to the axes of said crankshaft and said auxiliary shaft, bladed rotary axial flow suction fans each mounted on the other end of a respective one of said blower shafts for rotation therewith in a plane parallel to the axis of said crankshaft, the axis of each of said suction fans being perpendicular to the axis of said crankshaft, blades of each of said suction fans extending in close proximity to the air-cooling fins of some of said cylinders, and a plurality of mounted fan shroud members each having upper and lower open ends thereof and each surrounding a respective one of said suction fans adjacent the outer ends of said blades thereof for directing flow of air from the air-cooling fins of said cylinders to said suction fans, each of said shroud members terminating at said lower open end thereof between the respective one of said suction fans and said air-cooled fins, said suction fans by operation of said engine being simulta-

neously rotatable in a direction effecting the drawing of air from across the air-cooling fins of said cylinders and thence upwardly and outwardly through said upper open ends of said shroud members.

4. The improved air-cooled engine in combination as set forth in claim 3, wherein the blades of each of said suction fans consist of an inner set of blades for air and an outer set of blades as tips on said inner set of blades, said combination including engine exhaust jets connected to said engine and positioned adjacent said outer set of blades of each of said suction fans for driving the latter turbine-fashion with the aid of exhaust gases from said engine.

5. The improved air-cooled engine in combination as set forth in claim 3, including a set of stationary contra vanes positioned adjacent and extending across each of said suction fans to assure straight line air flow.

6. An improved air-cooled V-type multi-cylinder engine of the character described comprising, in combination, an internal combustion engine having a crankcase with a crankshaft therein and two rows of cylinders in V-formation, each of said cylinders being equipped with air-cooling fins, a rotatably mounted auxiliary shaft with the axis thereof above, adjacent and parallel to the axis of said crankshaft, gearing operably connecting said auxiliary shaft to said crankshaft for drive rotation by the latter, a rotatably mounted blower shaft operably geared at one end thereof to said auxiliary shaft and extending vertically upward therefrom between said two rows of cylinders in said V-formation, the axis of said blower shaft being perpendicular to the axes of said crankshaft and said auxiliary shaft, a bladed rotary axial flow suction fan mounted on the other end of said blower shaft for rotation therewith in a plane parallel to the axis of said crankshaft, the axis of said suction fan being perpendicular to the axis of said crankshaft, blades of said suction fan being adjacent the tops and air-cooling fins on inner sides of said cylinders of said two rows thereof in said V-formation, and a mounted fan shroud member having upper and lower open ends thereof and surrounding said suction fan adjacent the outer ends of said blades thereof for directing flow of air from said air-cooling fins to said suction fan, said shroud member terminating at said lower open end thereof between said suction fan and the air-cooling fins nearest the tops of said cylinders of both of said two rows thereof, said suction fan by operation of said engine being rotatable in a direction effecting the drawing of air from across the air-cooling fins of said cylinders and thence upwardly and outwardly through said upper open end of said shroud member.

7. An improved air-cooled V-type multi-cylinder engine of the character described comprising, in combination, an internal combustion engine having a crankcase with a crankshaft therein and two rows of cylinders in V-formation, each of said cylinders being equipped with air-cooling fins, a rotatably mounted auxiliary shaft with the axis thereof above, adjacent, and parallel to the axis of said crankshaft, gearing operably connecting said auxiliary shaft to said crankshaft for drive rotation by the latter, a plurality of rotatably mounted blower shafts each operably geared at one end thereof to said auxiliary shaft and extending vertically upward therefrom between said two rows of cylinders in said V-formation, the axes of said blower shafts being perpendicular

to the axes of said crankshaft and said auxiliary shaft, a plurality of bladed rotary axial flow suction fans each mounted on the other end of a respective one of said blower shafts for rotation therewith in a plane parallel to the axis of said crankshaft, the axes of said suction fans being perpendicular to the axis of said crankshaft, blades of said suction fans being adjacent the tops and air-cooling fins on inner sides of respective nearest ones of said cylinders of said two rows thereof in said V-formation, and a plurality of mounted fan shroud members having upper and lower open ends thereof and surrounding respective ones of said suction fans adjacent the outer ends of said blades thereof for directing flow of air from said air-cooling fins to respective ones of said suction fans, said shroud members terminating at said lower open ends thereof adjacent air-cooling fins nearest the tops of cylinders of both of said two rows thereof, said suction fans by operation of said engine being simultaneously rotatable in a direction effecting the drawing of air from across the air-cooling fins of said cylinders of both of said two rows thereof and thence upwardly and outwardly through said upper open ends of said shroud members.

8. An improved air-cooled horizontally-opposed multi-cylinder engine of the character described comprising, in combination, an internal combustion engine having a crankcase with a crankshaft therein and two rows of cylinders arranged horizontally opposite, each of said cylinders being equipped with air-cooling fins, a pair of rotatably mounted auxiliary shafts each adjacent a respective one of said two rows of cylinders, the axes of said auxiliary shafts being parallel to the axis of said crankshaft, gearing operably connecting said auxiliary shafts to said crankshaft for drive rotation by the latter, a pair of rotatably mounted blower shafts each operably geared at one end thereof to a respective one of said auxiliary shafts and extending upwardly and outwardly therefrom, the axis of each of said blower shafts being perpendicular to the axis of the respective auxiliary shaft, a pair of bladed rotary axial flow suction fans each mounted on the other end of a respective one of said blower shafts for rotation therewith in a plane parallel to the axis of said crankshaft, the axes of said suction fans being perpendicular to the axis of said crankshaft, blades of each of said suction fans being adjacent said air-cooling fins of cylinders of a respective one of said two rows thereof, and a pair of mounted fan shroud members having upper and lower open ends thereof, each of said shroud members surrounding a respective one of said suction fans adjacent outer ends of the blades thereof, said shroud members terminating at said lower open ends thereof above and adjacent air-cooling fins of cylinders of respective ones of said two rows thereof, said suction fans by operation of said engine being simultaneously rotatable in a direction effecting the drawing of air from across the air-cooling fins of cylinders of respective ones of said two rows thereof and thence upwardly and outwardly through said upper open ends of respective ones of said shroud members.

9. An improved air-cooled horizontally-opposed multi-cylinder engine of the character described comprising, in combination, an internal combustion engine having a crankcase with a crankshaft therein and two rows of cylinders arranged horizontally opposite, each of said cylinders being equipped with air-cooling fins, a rotatably mounted auxiliary shaft with the axis thereof

5 above and parallel to said crankshaft and equidistant from both of said two rows of cylinders, gearing operably connecting said auxiliary shaft to said crankshaft for drive rotation by the latter, a rotatably mounted blower shaft operably geared at one end thereof to said auxiliary shaft for rotation by the latter, the axis of said blower shaft being perpendicular to the axes of said cylinders, crankshaft and auxiliary shaft, a bladed rotary axial flow suction fan mounted on the other end of said blower shaft for rotation therewith in a plane parallel to the axis of said crankshaft, the axis of said suction fan being perpendicular to the axis of said crankshaft blades of said suction fan being adjacent air-cooling fins of cylinders of both of said two rows thereof, and a mounted fan shroud member having upper and lower open ends thereof, said shroud member surrounding said suction fan adjacent outer ends of the blades thereof for directing flow of air from said air-cooling fins of said cylinders to said suction fan, said shroud member terminating at said lower open end thereof above and adjacent air-cooling fins of cylinders of both of said two rows thereof, said suction fan by operation of said engine being rotatable in a direction effecting the drawing of air from across the air-cooling fins of said cylinders and thence upwardly and outwardly through said upper open end of said shroud member.

10. An improved air-cooled X-type multi-cylinder engine of the character described comprising, in combination, an internal combustion engine having a crankcase with a crankshaft therein and four rows of cylinders arranged in X-formation, each of said cylinders being equipped with air-cooling fins, two rotatably mounted auxiliary shafts with the axes thereof adjacent and parallel to the axis of said crankshaft, said auxiliary shafts being mounted on respective opposite sides of said crankshaft and within respective opposite angles each formed by two of said four rows of cylinders in X-formation, said auxiliary shafts being operably geared to said crankshaft for drive rotation by the latter, two rotatably mounted blower shafts each geared at one end thereof to a respective one of said auxiliary shafts for rotation by the latter, the axes of said blower shafts being perpendicular to respective ones of said auxiliary shafts, said blower shafts extending outwardly from said auxiliary shafts and within respective ones of said opposite angles each formed by two of said four rows of cylinders in X-formation, two bladed rotary axial flow suction fans each mounted on the other end of a respective one of said blower shafts for rotation therewith in a plane parallel to the axis of said crankshaft, the axes of said suction fans being perpendicular to the axis of said crankshaft, blades of each of said suction fans being adjacent air-cooling fins of two of said four rows of cylinders, and two fan shroud members having inner and outer open ends thereof, said shroud members surrounding respective ones of said suction fans adjacent outer ends of the blades thereof for directing flow of air from said air-cooling fins of said cylinders to respective ones of said suction fans, each of said shroud members terminating inwardly at said inner open end thereof adjacent air-cooling fins of said cylinders of a respective two of said four rows thereof, said suction fans by operation of said engine being rotatable in a direction effecting the drawing of air from across the air-cooling fins of said cylinders

ders and thence outwardly through said outer open ends of said shroud members.
